FUEL INJECTION PUMP FOR INTERNAL COMBUSTION ENGINES

Arthur Alexander Sidney, Thornton Heath, England, assignor to Bryce Limited, a company of Great Britain

Application July 11, 1932, Serial No. 621,957, and in Great Britain April 4, 1932

1 Claim. (Cl. 103—41)

The invention relates to improvements in pumps for supplying fuel to internal combustion engines, and more particularly to pumps of the type in which fuel is drawn or forced into a chamber from which it is expelled to the engine by a plunger sliding within the chamber.

The object of the invention is to provide means whereby the amount of fuel expelled from the chamber may be varied at will.

- 10 According to the invention the plunger is of constant stroke and is provided with passageways communicating at one end with the chamber, and co-operating at the other end with one or more ports in the walls of the chamber, whereby fuel is bypassed from the pump during the initial and final portions of the working stroke of the plunger, and is expelled from the chamber only during the mid portion of the stroke of the plunger. Further passageways are provided 20 in the plunger whereby the fuel may also be bypassed during the intermediate portion of the stroke. All the passageways in the plunger are symmetrically arranged about the axis thereof so that the plunger is always balanced.
- 25 The plunger is arranged for rotation relatively to the ports in the chamber so that the intermediate period of bypassing may be varied and thus also the working portion of the plunger's stroke. The ports in the chamber are conveniently of triangular form and may co-operate with circular cross-sectioned passageways in the pump plunger. The rotation of the plunger may be effected from the exterior of the pump so that the variation of output of the pump may be controlled at will in a simple and efficient manner.

A preferred embodiment of the invention is illustrated by way of example in the accompanying drawing in which:—

Figure 1 shows in vertical sectional elevation, 40 a fuel pump according to the invention,

Figs. 2, 3 and 4 are detailed views showing the pump plunger in different positions of its stroke,

Fig. 5 is a fragmentary view of a sleeve member incorporated within the pump, and

Fig. 6 is an enlarged view of a portion of this sleeve showing relative positions of a passageway in the plunger with respect to a port in the sleeve.

50 Referring to the drawing, the pump consists essentially of the plunger 1, which is mounted for reciprocation within a sleeve 2. The sleeve is secured in a casing 3, in the lower end of which is housed a cam 4, which operates a tappet 5 to produce the reciprocating motion of the

plunger 1. The casing 3 is provided with an inlet 6 communicating with a source of fuel for an engine. The upper end of the sleeve 2 is closed by a steel ball 7 biased on to a seating formed therein, by a spring 8 housed within the end of a union member 9 which is screwed into the upper end of the casing 3. The biasing force exerted by the spring 8 is sufficient to maintain the ball 7 on its seating until the pressure exerted by the fuel increases substantially above its supply value. The union 9 serves to retain the sleeve 2 in position axially, and has a bore 10 therethrough whereby the chamber enclosed by the upper end of the sleeve 2 and the plunger 1 may be put into communication with a pipe 70 leading to the engine.

The plunger 1 is drilled axially for a short distance with a hole 11, and two diametral holes 12 and 13 respectively, each crossing the hole 11 are drilled in the plunger perpendicular to one another. The diametral hole 13, which is remote from the upper end of the plunger, communicates at its outer end with a circumferential groove 14 recessed in the plunger.

On the lower end of the plunger 1 is cottered 80 a guiding member 15 provided with two diametral wings or ears 16 and 17 respectively, which are arranged to slide within longitudinal slots 18 and 19 respectively cut in a bushing 20. This bushing is mounted for rotation within a projecting boss 85 21 formed in the casing 3 and is secured from axial movement by means of a radially disposed screw 22, the inner end of which engages a circumferential slot 23 in the bushing 20. The bushing is provided with a plurality of longitudinal teeth 24 which are engaged by teeth in a rack member 25 slidably mounted for longitudinal movement in the casing 3. The movement of this rack can be initiated and controlled from the exterior of the casing and provides suitable means 90 for rotating the plunger 1 about its axis without affecting the reciprocating motion thereof.

The sleeve 2 within which the plunger 1 is disposed is provided with an external circumferential groove 26, and two oppositely disposed ports 100 27 are provided in said sleeve and communicate with said groove 26. The ports are substantially triangular in cross-section as shown in Fig. 5.

The diametral hole 12 within the plunger 1 is spaced from the upper end of the plunger such that the distance from its upper edge to the end of the plunger is less than the greatest depth of the port 27. The position of the groove 14 is arranged so that the distance of its upper edge from the lower edge of the diametral hole 12 is 110

also less than the greatest depth of the port 27. The plunger 1 is arranged relatively to the sleeve 2 so that at the lower end of its stroke, the upper end of the plunger is substantially in alignment 5 with the lowest edges of the ports 27, and at the upper end of its stroke, the lower edge of the groove 14 is still below the upper edges of the ports 27.

When the centre line of the hole 12 is in alignment 10 with the centre line of the ports 27 as shown at 12' in Fig. 6, no fuel passes to the engine because during the upward stroke of the plunger, the fuel in the chamber bounded by the sleeve 2, the ball 7 and the top of the plunger 1 is first 15 returned to the conduit 6 across the top of the plunger until this top passes above the upper edges of the ports 27 as shown in Fig. 2, then the fuel passes by way of the axial hole 11 and the diametral hole 12 until the lower edge of 20 the hole 12 passes the upper edges of the ports 27 as shown in Fig. 3, and finally it passes by way of the axial hole 11, the diametral hole 13 and the groove 14, as shown in Fig. 4, the upper edge of the groove 14 reaching the lower edge of 25 the ports 27 just as the lower edge of the diametral hole 12 passes the upper edges of these ports as shown in Fig. 3.

When the plunger is rotated so that the outer ends of the diametral hole 12 do not pass across 30 the ports 27 at all, as indicated at 12'' in Fig. 6, the pump operates to expel the maximum quantity of fuel, this quantity being pumped during the upward passage of the plunger from the point in its stroke when its upper edge passes 35 the upper edges of the ports 27 to the point where the upper edge of the groove 14 reaches the lower edges of the ports 27. These two extreme positions of stroke are shown respectively in Figs. 2 and 3, and are situated in the mid portion of the 40 complete stroke of the plunger, so that the pumping operation takes place during the period when the plunger is travelling at its highest velocity.

By rotating the plunger so that the ends of the diametral hole 12 pass across the inclined edges 45 of the ports 27, as shown at 12''' in Fig. 6, the quantity of fuel being pumped may be varied in a convenient manner from a minimum of zero at 12' to a maximum at 12'', the delivery always

occurring during the mid portion of the plunger's stroke.

It will be seen that owing to the construction and arrangement of the constituent parts of the pump, a plunger of symmetrical form may be obtained, the balance of which is not affected by rotation about its longitudinal axis. This feature in combination with the arrangement whereby the pump plunger which is of constant stroke only delivers fuel during the mid portion of its stroke, enables an exact predetermined quantity of fuel to be delivered, and also enables this quantity to be controlled within very exact limits.

I claim:—

A fuel injection pump for internal combustion engines, comprising a cylinder having a diametrically opposed pair of substantially triangular ports for connection at their outer ends with a source of fuel, each of said ports having one of its edges disposed obliquely to the axis of said cylinder, and a plunger adapted to be reciprocated with constant stroke in said cylinder to move its active face inwardly and outwardly beyond said ports, said plunger having a circumferential groove spaced from its active face a distance greater than the maximum dimension of said ports longitudinally of said cylinder and an axial bore extending from its active face to a point between its ends and communicating with said circumferential groove, said plunger also having between its active face and said groove a diametral hole communicating with said axial bore, the edge of said diametral hole nearest the active face of said plunger being spaced from said face an the edge of said circumferential groove nearest said diametral hole being spaced from said hole a distance less than the maximum dimension of said cylinder ports longitudinally of said cylinder, the circumferential groove of said plunger being adapted to communicate with the ports of said cylinder during the final portion of the instroke of said plunger for by-passing fuel from said cylinder and said plunger being rotatable about its axis to adjust said diametral hole relatively to the oblique edges of said cylinder ports.
